LOOM DOBBY

Elbridge R. Holmes, Worcester, Mass., assignor
to Crompton & Knowles Loom Works, Worcester,
Mass., a corporation of Massachusetts

Application December 21, 1936, Serial No. 116,975

6 Claims. (Cl. 139—71)

This invention relates to dobbies used for selecting and shifting harnesses in multi-harness looms. These harnesses are arranged in closely parallel relation but are necessarily positioned at substantially different distances from the fell of the cloth, particularly when a considerable number of harnesses, such as twenty, are used. Consequently the rear harnesses must be given a substantially greater lift than the front harnesses to effect equal shed openings.

Upper and lower dobbey hooks are connected through dobbey back levers to the harness jacks and these hooks are selectively engaged and actuated by upper and lower dobbey knives. It has been customary to operate these knives in such manner that the rear end portion of each knife, which engages the hooks for the back harnesses, would have a greater and more rapid travel than the front portion, which engages the hooks for the front harnesses.

As a result, the knives have been obliquely inclined in one direction when they engaged the hooks, have been substantially perpendicular to the path of travel of the hooks at mid-stroke, and have been again obliquely inclined but in the opposite direction at the end of the lifting stroke. The spacing of the points of contact of the hooks along the knives has thus been constantly and reversely varied, so that relative sliding motions have taken place between the knives and the hooks while these parts were under substantial load. These relative sliding motions have caused substantial wear between the parts and have also caused substantial lateral strains on the hooks and associated parts.

It is the object of my invention to provide an improved construction in a dobbey, by which the desired diversity of harness lift may be effected by knives which remain perpendicular to the paths of travel of the hooks throughout their whole strokes, with all working positions of the knives substantially parallel.

To the accomplishment of this object, I preferably provide harness jacks of different proportions and leverage. A further important feature of my invention relates to the provision of an improved and novel supporting and bearing structure for the differently proportioned harness jacks.

My invention further relates to arrangements and combinations of parts which will be herein-after described and more particularly pointed out in the appended claims.

A preferred form of the invention is shown in the drawing, in which

Fig. 1 is a sectional side elevation of portions of a loom dobbey embodying my improvements;

Fig. 2 is a sectional end elevation, taken along the line 2—2 in Fig. 1; and

Fig. 3 is a side elevation of certain parts to be described.

Referring to Fig. 1, I have shown a plurality of harness jacks 10, 11, 12, 13 and 14, several jacks of each kind being commonly provided. In Fig. 2 I have indicated four jacks 10 and a corresponding number of jacks 11, 12, 13 and 14 may be assumed.

Each harness jack is provided with a dobbey back lever 20, pivoted to its associated jack at 21 and having upper and lower dobbey hooks 22 and 23 pivoted thereto at the points 24 and 25.

The levers 20 engage cross bars 27 which constitute stops to limit movement of the levers to the right in Fig. 1. The pivots 21 for all dobbey back levers are substantially aligned when the jacks are in lowered position.

The hooks 22 and 23 are positioned for engagement by an upper dobbey knife 30 and by a lower dobbey knife 31 respectively. These knives are alternately reciprocated by any suitable actuating mechanism, and are at all times substantially perpendicular (transversely) to the hooks 22 and 23 and to the paths of travel of the hooks.

The harness jacks 10 to 14 are provided with end bearing portions or knobs 40, 41, 42, 43 and 44 respectively, which constitute centers for the swinging motion of the harness jacks. In order to provide supporting bearings for the knobs 40 to 44, I use a series of bearing plates 50, 51 and 52. Each of these plates is provided with a bearing notch 55 and with holes 56 to receive tie-rods or bolts 57 and 58 (Fig. 2). By reversing the plates 50 and 51 (Fig. 3), these three different kinds of plates 50, 51 and 52 may be combined to provide bearing notches 55 at the five different elevations indicated in Figs. 1 and 3. The bearing plates 50 provide bearing notches 55 for the harness jacks 10 and 14, the plates 51 provide bearing notches for the jacks 11 and 13, and the plates 52 provide bearing notches for the jacks 12. Separator plates 60 are mounted between the plates 50, 51 and 52 to maintain the harness jacks in spaced and operative position.

With a dobbey thus constructed, all of the upper dobbey hooks will be given equal travel and all of the lower dobbey hooks will also be given equal travel. The pivots 21 in the harness jacks will thus all swing in arcs of equal length.

The difference in jack proportions and lever-

age is such, however, that the jacks 10 will have the greatest swinging movement at the upper end where the harnesses are connected, and that the jacks 14 will have the least swinging movement.

5 Consequently the jacks 10 are to be connected to the back harnesses to give them the greatest lift, while the jacks 14 are to be connected to the front harnesses to give them the smallest lift, the other jacks being connected to intermediate harnesses in successive groups.

The necessary difference in lift to maintain theoretically equal shed opening is relatively small within each group, and the provision of equal lift for all of the harness jacks in each 15 small group closely approximates equal shed opening. For closer adjustment, each jack is provided with the usual series of notches by which the lift of each harness may be further adjusted.

20 By my improved construction I retain the advantages of the old construction so far as substantially equal shed opening is concerned, while at the same time I avoid the oblique working positions of the dobby knives and the resultant 25 lateral strains and relative sliding movements between the knives and dobby hooks.

Having thus described my invention and the advantages thereof, I do not wish to be limited to the details herein disclosed, otherwise than 30 as set forth in the claims, but what I claim is:—

1. In a dobby, a plurality of harness jacks of different proportions and leverage, a dobby back lever pivoted to each jack, upper and lower dobby hooks for each lever, means to give said hooks 35 and levers equal travel, and means to provide pivotal supporting bearings for said jacks at different but graduated distances from the points of pivotal connection between said jacks and said dobby back levers.

40 2. In a dobby, a plurality of harness jacks having lower end portions of different lengths and having the remaining portions substantially identical, and bearing means for said different end portions effective to support said jacks with

the identical upper portions substantially at the same level.

3. In a dobby, a plurality of harness jacks having lower end portions of different lengths and having the remaining portions substantially 5 identical, and bearing means for said different end portions effective to support said jacks with the identical upper portions substantially at the same level, said bearing means comprising bearing plates having notches at different distances 10 from the ends thereof, and certain of said plates being reversible to coact with jacks of two different end lengths.

4. A plurality of harness jacks, a pair of actuating dobby knives selectively connected to 15 indicated jacks, and means to give all parts of each knife equal travel whereby all operative positions of each knife are parallel, said harness jacks being of such relative proportions and leverage that said defined movements of said 20 knives will effect movements of said jacks which increase progressively toward the back of the loom.

5. In a dobby, a plurality of harness jacks, upper and lower dobby hooks, connected through 25 dobby back levers to said harness jacks, and means to give every upper hook equal travel and every lower hook equal travel, said harness jacks being of such relative proportions and leverage that said equal movements of said hooks will 30 effect movements of said jacks which increase progressively toward the back of the loom.

6. In a dobby, a plurality of harness jacks, a pair of actuating dobby knives selectively connected to indicated jacks, the engaging surface 35 of each knife being positioned at all times perpendicular to the path of travel of said knife, and means to give all parts of each knife equal travel, said harness jacks being of such relative proportion and leverage that said defined movements 40 of said knives will effect movements of said jacks which increase progressively toward the back of the loom.

ELBRIDGE R. HOLMES.
